UNITED STATES PATENT OFFICE.

LA VERNE W. NOYES, OF CHICAGO, ILLINOIS.

SKELETON TOWER.

No. 877,587.

Specification of Letters Patent.

Patented Jan. 28, 1908.

Application filed July 20, 1906. Serial No. 327,056.

To all whom it may concern:

Be it known that I, LA VERNE W. NOYES, a citizen of the United States, residing at Chicago, in the county of Cook and State of Illinois, have invented new and useful Improvements in Skeleton Towers, of which the following is a full, clear, concise and exact description, reference being had to the accompanying drawing, forming a part of this

specification.

My invention relates to electric wire towers, and more particularly to built-up towers of structural iron.

The object of my invention is to provide a tower of this character which will be strong and stable, and which will effectually withstand the strains to which such a tower is subjected.

A further object of my invention is to construct a tower of this character which may be readily raised, and to this end I preferably construct my tower so that the same may be formed of two parts, each part being arranged to be raised separately, and after being raised connected to the other part.

A still further object of my invention is to provide a tower arranged to carry sets of transmission wires, the portion of the tower carrying one set of wires being thoroughly insulated from that portion carrying the other set of wires.

I have illustrated my invention in the accompanying drawings, in which

Figure 1 is a side elevation of my tower; Fig. 2 is a detail of the manner of securing the bracing rods of my tower; Fig. 3 is another side elevation of my tower, showing a view at right angles to Fig. 1; Fig. 4 is a detail of one of the plates used for connecting the two sections of tower together; Fig. 5 is a detail sectional view showing the manner of insulating the sections of the tower; and Fig. 6 is a sectional view taken on the line 6—6 of Fig. 3.

As appears from the drawings, the particular skeleton tower which I have illustrated for the purpose of disclosing my invention, consists of a pair of upright arms or end frames designated as a whole by 1, 1, each constructed to form a rigid and unyielding structure as hereinafter set forth in detail.

The end pieces or frames of the tower are triangular in shape as shown in Fig. 1, and are formed of two converging posts 3, 3, the

lower ends of which form the supporting legs 55 2, 2, while the upper ends, being mechanically united in any suitable manner, form the tops of the arms or end frames 1, 1. I prefer to unite these upper extremities as illustrated, wherein the angle bars comprising 60 the posts 3, 3, have their opposed flanges dovetailed to securely fit together, the same being bound together by means of clamps 4.

Extending from a point near the middle of each post 3 to a point near the bottom of the 65 opposite post, are bracing posts 5, 5, which are preferably secured together by means of a suitable connection 6 at their intersection. These posts 5, 5, are braced to the upright posts 3 by means of lateral bars 7, extending 70 perpendicularly to a line bisecting the angle between the posts 5 and 3, as shown in Fig. 1, and are thus of the shortest possible length to extend between the two posts, and occupy 75 positions wherein they impart maximum strength to the structure. The uppermost of these lateral bars 7, are secured to the connection 6 at the point of intersection of the bracing posts 5, 5, as clearly shown in Fig. 1. The rods 8, extend between the lateral bars 80 7, to secure the tie members of the structure together. The lateral bars 7, are preferably angle rods and the tie rods preferably secured thereto, as indicated in Fig. 2, with reference to bar 10 and tie rod 11; wherein the 85 enlarged head on the tie rod is shown as fitting into a key hole slot in the bar.

A transverse bar 9 extends between the posts 3, 3, near the middle, and transverse bars 10 extend between the posts 3, 3, on the 90 upper section thereof. The longer of these transverse bars 10 are secured together by means of tie rods 11. The bracing posts and bars, or beams, are preferably made of angle iron, and the posts are disposed so that the 95 same may rest in flat contact without the necessity of cutting away the flanges. The ends of the longer bracing post or beams are preferably formed of double thickness by flattening the flanges so that they will rest in 100 parallel position. The upper ends of the posts 3, 3, are also connected by bracing bars 12, as illustrated, to give additional strength to this portion of the tower. It will of course be understood that while I have 105 described the particular bracing means and other parts of the tower specifically with reference to the structure I have illustrated for

disclosing my invention, other arrangements and modifications may be used without departing from the spirit of my invention.

The structure above described consists of a triangular frame which may be termed the end frame, and there are two of these end frames, one at each end of the tower, occupying parallel positions. To each end frame is secured a pyramidal frame comprising a post 10 or leg 12', secured to the top of the end frame and two posts 13 connected at their lower end to the bottom of the posts 3, the three posts 12', 13, 13 converging at a point 15 intermediate of the ends of the frame, as 15 clearly shown in Figs. 1, 4 and 6. A plate 16 secures the converging ends of the posts together. It will thus be seen that each section of the tower presents a side view triangular in shape, as clearly shown in Fig. 3, with 20 the common point of convergence 15 as the apex. Also, each section presents a triangular shape when viewed from above, as clearly shown in Fig. 6, with the point of convergence 15, as before, as the apex. Therefore, 25 the two sections converge at a common point, as contradistinguished from meeting in a common line, such as is the case in prior structures where a top view similar to that of Fig. 6 would show the two triangles meeting 30 in a line and not converging at a point.

The construction of the connecting plates is shown in Figs. 4 and 5, wherein is illustrated a plate, having an angle socket 16^a, in which is bolted the lower end of the post 12', 35 and two diverging angle sockets 16^b, in which are bolted the upper converging ends of the posts 13. The sockets are inclined from the vertical to accommodate the inclination of the various posts attached thereto, 40 and the center of the plate is formed substantially flat to provide a portion in which the bolts, for connecting the sections of the tower, may be secured. When the two sections of the tower are raised, the two plates 45 16 are opposite one another, and to connect the sections of the tower, and at the same time insulate the two sections from one another, a block of insulating material 16^c having embedded therein oppositely disposed 50 bolts 16^d, is placed between the plates and the bolts secured thereto. It is obvious that, if desired, the block of insulating material may be dispensed with and the plates connected directly together by means of bolts. 55 However, as the two arms or end frames 1 of the tower are under certain conditions arranged to carry two sets of wires, each set having wires of different potential, it is desired to insulate the two sections and I have 60 therefore provided the above means of insulation. The purpose of the insulation between the two halves of the double-circuit tower is to reduce the danger from static stresses in cases where the tower is imper-

fectly grounded. With the tower-structure 65 under static stress, it would be unsafe for a man to attempt to climb it for the repair of damage to one circuit when the other circuit is alive, unless the halves or sections carrying the circuit-wires were separated from each 70 other by insulation. Of course, if the tower is perfectly grounded, there will be no induced static stresses in it. But, where the grounding of the tower is not perfect (and this is likely to occur), the insulator between 75 the two halves of the tower would greatly reduce the static effect on the side of the tower on which the circuit is not in operation, thus rendering it more safe for the workman to repair this circuit with the other circuit energized. 80

While I have shown and described a means for insulating the specific sections of towers described, I do not wish to be limited thereto as I may insulate sections of towers having 85 various constructions without departing from the spirit of the appended claims.

The posts 13 are braced to the posts 2 by means of lateral bars 17 which are connected in substantially the same manner as are the 90 bars 7, and these lateral bars 17 are connected by bracing rods 17'. The posts 12' and 3 are braced by means of bracing bars or beams 18 and tie rods 19. Bracing beams 20 extend from the posts 3 to the converging 95 point of the posts 13 and 12'.

It will be noted from the foregoing description that the skeleton tower, which I have illustrated, comprises two triangular end frames having pyramidal bracing frames, 100 which, when the two portions of the tower are joined together, form (see Fig. 1), two upwardly extending three-post arms (the three posts being 3, 3, 12'), and four downwardly extending three-post legs the three 105 posts being 3, 13, 5. These legs diverge while the longitudinal members of each leg converge toward the lower ends.

For connecting the various wires to the tower, cross arms 21, having insulating pins 110 22 mounted thereon, are secured at suitable intervals to the upright arms or end frames 1 of the towers. Vertically extending arms 23, to which the ground wires may be connected, are secured between the converging 115 ends of the posts 3 and 12'. It will thus be seen that the inner insulating pins are arranged on the said posts at points intermediate the outer pins. By means of this staggered position of the pins I provide the 120 greatest distance between them, and therefore between the wires of different potential that may be carried by said pins.

While I have described my invention as being constructed particularly for use in 125 supporting transmission lines, it will be understood that there are various other uses to which the tower may be put.

Having thus described my invention what I claim as new and desire to secure by Letters Patent is:

1. A tower having a pair of upright end frames of triangular form and a pair of bracing frames pyramidal in form. 5
2. A tower composed of two sections, each having an upright end frame of triangular form and a bracing frame pyramidal in form, 10 said sections being connected at the apices of said pyramidal bracing frames.
3. A tower having a pair of triangular upright end frames of structural iron, comprising converging posts suitably braced, and 15 bracing frames comprising posts fastened to each end of the triangular frames and converging at one point.
4. A tower having a pair of upwardly extending three post supporting arms and four 20 downwardly extending three post legs.
5. A tower having a pair of upwardly extending three post supporting arms and four downwardly extending laterally diverging legs. 25
6. A tower having a plurality of downwardly extending three post legs, the post of each leg converging toward the lower ends, and each leg having a post converging towards and connected to a post of each of the 30 remaining legs.
7. A tower comprising a pair of triangular upright end frames and diagonal bracing posts for each frame converging at a common point. 35
8. A tower comprising two triangular end frames and angularly extending members coöperating therewith to form a plurality of upwardly extending triangular pyramidal arms. 40
9. A skeleton tower comprising two triangular end frames and angular members coöperating therewith to form two upwardly extending triangular pyramidal arms and four downwardly extending triangular pyramidal 45 legs.
10. In a tower structure, a pair of sections having end frames, converging posts secured to each frame, means for connecting together the free ends of the posts of each frame, and 50 separate means for connecting the sections together at the points of convergence.
11. In a tower structure, a pair of sections having end frames, three converging posts secured to each frame, means for connecting together the free ends of the posts of each frame, and 55 separate means for connecting the sections together at the points of convergence.
12. A tower composed of two sections having means for insulating said sections from each other. 60
13. In a tower structure, a pair of sections having end frames, converging posts secured to each frame, means for connecting together 65
- the free ends of the posts of each frame, and 65 separate insulating means for connecting the sections together at the points of convergence.
14. A tower composed of two sections detachably connected and insulated from each 70 other.
15. In a tower structure, a pair of sections, each formed of a pyramidal arm and two pyramidal legs, said arms and legs of each section having converging portions connected 75 together, and separate means for connecting the sections together at the points of convergence.
16. A tower composed of two sections insulated from each other, and each formed of 80 a pyramidal arm and two pyramidal legs.
17. A tower composed of two sections converging at a common point and connected together at the point of convergence.
18. A tower composed of two sections converging at a common point and detachably connected together at the point of convergence. 85
19. A tower composed of two sections converging at a common point and connected 90 together at the point of convergence, said sections being insulated from each other.
20. A tower composed of two sections, each having an upright end frame of triangular form, and bracing of pyramidal form, said 95 sections being insulated from each other and connected at the apices of the pyramidal bracing frames.
21. A tower having a pair of upright end frames, triangular in form and comprising 100 two converging posts and a pair of bracing frames pyramidal in form and each comprising three converging posts, said posts being connected at their point of intersection to a plate having sockets conforming to the shape 105 of said posts and said plates forming a means for connecting the two sections of the tower together.
22. A tower having a pair of upright end frames, triangular in form and comprising 110 two converging posts and a pair of bracing frames pyramidal in form and each comprising three converging posts, said posts being connected at their point of intersection to a plate having sockets conforming to the shape 115 of said posts and said plates forming a means for connecting the two sections of the tower together, and having a block of insulation interposed between the plates of each section.
23. A tower having a plurality of posts arranged to carry electrical conductors, and means for insulating said posts from one another. 120
24. A tower composed of a plurality of sections, each section having a base for carrying 125 electrical conductors, and means for insulating said sections from one another.
25. A tower formed of two sections, each

section having a base arranged to carry one or more electrical conductors, and means for insulating said sections from one another.

26. A tower having a plurality of posts, 5 each post carrying a plurality of insulator pins, said pins being arranged in a staggered position upon said posts to provide the greatest distance between the pins.

27. A tower having a plurality of posts, 10 each post having arranged thereon outer and

inner insulating pins, the inner insulating pins being arranged on the tower at a point intermediate of the outer pins.

In witness whereof, I have hereunto subscribed my name in the presence of two wit- 15 nesses.

LA VERNE W. NOYES.
